UNITED STATES PATENT OFFICE

FRED C. AUFPDERHEIDE, OF ST. LOUIS, MISSOURI

BURIAL VAULT

Application filed December 27, 1929. Serial No. 416,770.

This invention relates to burial vaults.

An object of the invention is to provide a burial vault that is impervious to water. The invention may be embodied in a vault comprising an impervious metallic lining veneered or enameled or enclosed by non-corrodible material. Or, the device may be embodied in a construction not including metallic walls, such, for instance, as glass or other vitreous material, or porcelain, or other substances or material capable of satisfactory use for this purpose. In suggesting these specific materials, I do not in any particular restrict myself, and these materials are mentioned only as illustrative of embodiments of the invention.

Another object of the invention is to provide an improved burial vault of impervious structure comprising a lid or cover jointed with the vault by an impervious joint and constructed to shed and deflect water and moisture in a direction away from the side walls of the vault.

Other objects will appear from the following description, reference being made to the accompanying drawings in which—

Fig. 1 is a perspective view of a vault embodying the present invention.

Fig. 2 is a side elevation with parts broken away and in section to disclose various features of the invention.

Fig. 3 is a vertical cross sectional view approximately on the line 3—3 of Fig. 2.

Fig. 4 is an enlarged detail sectional view approximately on the line 4—4 of Fig. 2.

Fig. 5 is a view with parts in section and broken away to disclose a variant of the invention.

Fig. 6 is a vertical cross sectional view approximately on the line 6—6 of Fig. 5.

Fig. 7 is an enlarged sectional view showing the connection of the lid with a side wall of the vault.

Fig. 8 is a view similar to Fig. 5 showing the vault made of a different material.

Fig. 9 is a vertical cross sectional view approximately on the line 9—9 of Fig. 8.

The vault shown in Figs. 1 to 4, inclusive, comprises impervious material forming a lining and strong and durable material en-

closing the lining. The lid of the vault comprises an impervious lining portion and an outer portion inseparably united with the inner portion and strengthening the same. The lid is united with the walls of the vault proper by an impervious joint and is constructed and arranged to shed and cast off water and moisture out of contact with the walls of the vault.

The inner portion of the vault shown in Figs. 1 to 4, inclusive, comprises a bottom wall 1 having projections 2 on its lower side; longitudinal side walls 3 rising from integral connection with the side edges of the bottom wall 1 and having projections 4 on their outer sides; and end walls 5 rising from integral connection with the ends of the bottom wall 1 and having their side edges integral with the ends of the end walls 3 and having on their outer edges projections 6. These walls 1, 3 and 5 are impervious as to moisture and may be made of glass or other vitreous material or of any other material appropriate for the purpose, such as suitable metallic substances.

This box-like structure comprising the walls 1, 3 and 5 is enclosed in and surrounded by a monolithic box comprising a bottom wall 7, side walls 8 integrally connected with and rising from the side edges of the bottom wall 7 and end walls 9 integrally connected with the ends of the bottom walls 7 and the ends of the side walls 8. The projections 2 and 4 and 6 are embedded in the monolithic walls so that it is impossible for the inner impervious box-like device to be detached or removed from the lithic enclosure.

The upper edges 10 of the walls 8 and the upper edges 11 of the walls 9 incline downwardly and outwardly. The walls 8 and 9 are of the same height.

The inner walls 3 and 5 extend above the upper edges of the walls 8 and 9 and are formed with an inner ogee structure 12, being a flange of approximately the same thickness as said walls. This ogee flange curves inwardly and then upwardly and along the outer side of its upper edge has a bead or rib 13. The upper side of the inwardly curved portion of the flange 12 is in con-

tinuation of the upper edges 10 and 11 of the walls 8 and 9.

The upper portions of the walls 8 are formed with recesses 14 across each of which 5 a pin 15 extends. A leaf-spring 16 extends into each of the recesses 14, the lower ends of said springs being embedded in the walls 8.

The lid of this vault comprises an impervious inner member 17 which may be made 10 of any suitable material, such as vitreous substance, and has on its upper side a number of projections 18. The side and end edges of the member 17 are in the form of downwardly and inwardly curved flanges 19. A 15 lithic enclosure 20 for the member 17 is provided and embeds the projections 18 and also the outer side portions of the flanges 19, so that it is impossible for the parts 17 and 20 to become separated. The lithic member 20 has downwardly and outwardly inclined 20 portions 21 which extend outwardly beyond the outer sides of the walls 8 and 9 so as to deflect water and moisture outwardly away from said walls 8 and 9. The lower edges 25 22 of the parts 21 are inclined in the manner of the edges 10 and 11. Metallic elements 23 are embedded transversely in the lithic structure 20 and have their ends bents and extended upwardly to provide loops 24 to receive straps or bands whereby the lid may be lowered onto the vault from above. The lid may be equipped with latches 25 having their upper ends mounted on pivots 26. The latches 25 are designed and arranged to extend downwardly into the recesses 14 and to be snapped under the pins 15 automatically and as an incident to the lowering of the lid to proper position, as will be understood by reference to Fig. 2. The springs 16 permit the latches 25 to move downwardly into latching engagement with the pins 15 and prevent said latches from working out of engagement with said pins 15.

An impervious joint between the lid and 45 the vault is provided by placing on the upper edge of the vault a layer 27 of cementitious or other appropriate plastic material which will harden and form an impervious seal after the lid is placed thereon. The edges 19 50 of the lid inner member 17 presses the joint forming substance 27 into close contact with the grooved outer side of the flange 17 while other portions of the lid press the substance 27 in a manner such that when said substance 55 hardens an impervious joint is provided.

The improved vault, shown in Figs. 5, 6 and 7, is of a vitreous or lithic substance comprising a bottom wall 28, longitudinal side walls 29 rising from integral connection 60 with the side edges of the wall 28 and end walls 30 integrally connected with the ends of the bottom wall 28 and with the ends of the side walls 29. The upper edges of these walls 28 and 29 are curved inwardly and 65 upwardly to provide a joint flange 31 hav-

ing along the outer side of its upper edge a flange 32. The lid or cover of this vault is composed of vitreous or other appropriate impervious material and comprises a top portion 33 having a downwardly extended flange 34 along its side and end edges. The inner side of the flange 34 has a bead 35 designed and arranged to compress the plastic joint forming substance 36 into close sealing contact with the flange 31. The edges of the flange 34 extend outwardly beyond the outer sides of the walls 29 and 30, so as to cast off water and moisture.

The vault shown in Figs. 8 and 9 is quite similar in construction and arrangement to that shown in Figs. 5, 6 and 7 and may be considered as an illustration of an embodiment of the invention comprising any material having its outer surface rendered impervious. Porcelain is one such material. This vault comprises a bottom wall 37, longitudinal side walls 38 rising from integral connection with the side edges of the wall 37, and end walls 39 integrally connected with the ends of the wall 37 and with the ends of the wall 38. The upper edges of the walls 38 and 39 are formed with a flange 40 having along the outer side of its upper edge a bead 41. The lid may be made with the same material as the body of the vault and comprises a top portion 42 having along its side and end edges a depending flange 43. The flange 43 is formed along its inner side with a bead 44 which will compress the plastic joint forming substance 45 closely against all portions of the outer side of the flange 40, so as to form an impervious joint.

These lids are formed with integral loop handles 46 through which straps or the like may be passed to lower the lids onto the vaults.

In mentioning the different elements and substances which may be used satisfactorily in the manufacturing of this invention, I have not intended to restrict myself to the use of these specific substances. For, it is clear that other substances may be used with equal satisfaction. And it is clear that the construction and arrangement of the device may be varied within equivalent limits without departure from the nature and principle thereof. I do not restrict myself in any unessential respects, but what I claim and desire to secure by Letters Patent is:

1. A burial vault comprising lithic bottom, side and end walls integrally united with each other and forming a box-like structure, vitreous bottom, side and end walls integrally united with each other and lining said lithic box-like structure and forming an impervious inner surface therefor, means holding said vitreous walls rigidly in connection with said lithic walls, a lid for the vault, and means for securing said lid on the vault.

2. A burial vault comprising lithic bottom,

side and end walls integrally united with each other and forming a box-like structure, vitreous bottom, side and end walls integrally united with each other and lining said lithic box-like structure and having their upper edges extending above the upper edges of said side and end walls and forming an impervious inner surface for said lithic walls, a lid for the vault telescoping about the upper portion of said vitreous walls, and means between said lid and said lithic and vitreous walls forming an hermetic joint.

3. A burial vault comprising vitreous bottom, side and end walls integrally united with each other and forming a receptacle, a flange integral with said side and end walls extending inwardly and upwardly therefrom, an outwardly extended bead integral with the outer side of the upper marginal portion of said flange, a lid telescoping about said flange, and means confined between the lower edge of said lid and the upper edges of said side and end walls and also between said flange and the inner surface of said lid forming an hermetic joint between said lid and said walls.

4. A burial vault comprising lithic bottom, side and end walls integrally united with each other and forming a box-like structure having the upper edges of said side and end walls inclining downwardly and outwardly, vitreous bottom, side and end walls integrally united with each other and lining said lithic box-like structure and forming an impervious inner surface for said lithic walls, an inwardly and upwardly extended flange integral with the upper portions of said vitreous walls extending above the upper edges of said lithic walls, a lid telescoping about said flange, and means located between said lid and said lithic walls and said vitreous flange forming an hermetic joint.

5. A burial vault comprising lithic bottom, side and end walls integrally united with each other and forming a box-like structure having the upper edges of said side and end walls inclining downwardly and outwardly, vitreous bottom, side and end walls integrally united with each other and lining said lithic box-like structure and forming an impervious inner surface for said lithic walls, an inwardly and upwardly extended flange integral with the upper portions of said vitreous walls extending above the upper edges of said lithic walls, a lid telescoping about said flange, means located between said lid and said lithic walls and said vitreous flange forming an hermetic joint, means for securing said lid in rigid relationship with respect to said lithic and vitreous walls, and extended portions in connection with said lid extending beyond the outer surface of said lithic walls and guarding and shielding said joint.

66 FRED C. AUFDERHEIDE.
